UNITED STATES PATENT OFFICE.

CHARLES McMILLAN, OF CHICAGO, ILLINOIS.

FURNACE.

SPECIFICATION forming part of Letters Patent No. 295,188, dated March 18, 1884.

Application filed October 25, 1882. (No model.)

To all whom it may concern:

Be it known that I, CHARLES McMILLAN, a citizen of the United States, residing in Chicago, county of Cook, and State of Illinois, 5 have invented certain new and useful Improvements in Furnaces, of which the following is a specification.

My invention relates to improvements in furnaces, more particularly adapted and herein 10 after described as applied to steam-boiler furnaces, in which a bridge-wall is arranged forward of the rear end of the boiler, and the space between the bridge-wall and the rear end of the furnace forms a combustion-chamber 15 for the products of combustion of the fire-chamber escaping over the bridge-wall.

The objects of my invention are to provide such a furnace with a reverberatory surface, the effect of which shall so augment the heating 20 capacity of the furnace as to permit a material reduction in size of fire-chamber, and a corresponding reduction in the amount of fuel necessary to be employed to attain a given degree and area of heat; to provide means for effectively removing from the reverberatory 25 portions of the furnace the accumulation of ashes, fine particles of coal, sand, and other substances which have the effect of diminishing and destroying the reverberating and reflecting powers of such portions, and to make 30 such removal without cooling or stopping the operation of the furnace; to provide means for supplying and regulating currents of air supplied to the products of combustion; to promote perfect combustion in the combustion-chamber in the rear of the bridge-wall, and for utilizing the heat of the furnace for heating 35 said air-currents before contact with products of combustion; to provide a novel form 40 of bridge-wall which shall afford the least possible resistance to flames striking against it from passing over it into the combustion-chamber, and which wall will also cause the coal striking against it, when firing, to bank 45 up against and not rebound from the wall; to provide the furnace with an ash-pit of a form best adapted for effective cleaning, and for reverberating the heat deflected from the burning fuel on the grate-bars; to provide means 50 for dividing the air-current upon its entrance to the combustion-chamber, and for closing the

outlets during the removal of the accumulated ashes, &c., from the combustion-chamber and ash-pit, and correspondingly reducing the draft of the furnace, to prevent the finer particles from rising and clogging the flues of the boiler; to provide the boiler with a covering 55 adapted to prevent the radiation of heat from the top of and to adjust itself to the contraction and expansion of the boiler, and relieve 60 the walls of the furnace from such contracting and expansive force; and, finally, in details of construction, hereinafter described and claimed. I attain these objects by devices 65 illustrated in the accompanying drawings, in 5 which—

Figure 1 is a longitudinal section of a steam-boiler furnace embodying my invention; Fig. 2, a detail transverse section of the swinging air-outlet bars in the combustion-chamber; Fig. 3, a rear elevation of my furnace; Fig. 4, a transverse section of the same on the line *x x* of Fig. 1; and Fig. 5, a similar view on the line *y y*, Fig. 1. Fig. 6 is a detail side elevation of the lugs and the bars thereon, supporting the cover; Fig. 7, a detail horizontal section, showing the concaved portion *i*.

Similar letters of reference indicate the same parts in the several figures of the drawings.

A A represent the end walls, and B B the 80 side walls, of the furnace, the rear end wall and the side walls of which are respectively provided, toward their top, with a flange or horizontal extension, *a* and *b*, from which the boiler C is suspended by means of suitable 85 angle-irons or anchors, *c*, or other suitable means. The front end of the furnace is provided with the usual furnace-opening, D, closed by a door, through which opening fuel is thrown upon the grate-bars E, which bars are 90 of the ordinary construction, and may be supported on an angle-iron, *e*, and projected into the bridge-wall, as shown, or in any other usual or desirable manner. Ash-pit F has its 95 sides protected by linings *f f*, (see Fig. 4.) which linings extend above the grate-bars, are convexed on their upper edges, and form linings for the sides of the fire-chamber, and are removable, so as to be replaced by new linings when burned out. The bottom of the ash-pit 100 is removable, and inclined from the front toward the rear of the furnace, and where it

joins the bridge-wall at *g* is concaved with the bridge-wall, so that when an ordinary scraper is introduced the ashes may be effectually and cleanly removed, which could not be if the 5 jointure of the ash-pit with the bridge-wall formed an angle.

Inclining and curving the ash-pit in the above-described manner is an important feature of my invention, for the reason that it 10 not only facilitates the removal of the ashes, but reverberates the heat deflected from the fuel and grate-bars, causing a more rapid combustion of the fuel, which, together with the reverberated heat itself, materially increases 15 the heating capacity of the furnace. The reverberating effects of the ash-pit may be augmented by convexing the bottom as well as inclining the bottom of the ash-pit, or by convexing said bottom without inclining it; but 20 the construction shown is preferred, on account of its affording a better surface to draw the ashes and the scraper when removing the ashes. The ash-pit should of course be provided with a suitable door and with drafts, not 25 here necessary to be shown. Bridge-wall *G* is the bridge-wall proper of the furnace, and is built and arranged in the usual manner, except so far as broadening and convexing its rear side, as hereinafter described. *H* is a supplemental bridge-wall conforming in height to the bridge-wall proper and having close contact therewith, and convexed on its upper corner next the fire-chamber, as shown at *h*, which convexity terminates just above the grate-bars. 30 The extremities *i* of the supplemental bridge-wall, which follow the curved continuation of and rise with the curved face of the bridge-wall proper, are concaved, so as to fill in the angle otherwise formed by the juncture of the bridge-wall with the straight side walls of the fire-chamber. The supplemental bridge-wall effectually protects the bridge-wall proper, and may be readily removed when 35 burned out without disturbing the latter.

45 Convexing and concaving the supplemental bridge-wall gives it two important functions—first, that of its affording less resistance to and enabling the flames striking against it or its extension *i* to glance over and be carried by 50 the draft farther toward the rear of the furnace than if a vertical face and angular corner opposed the flame; and, second, that of affording a surface down which the coal thrown against the bridge-wall will slide and bank up 55 against the face of the wall instead of rebounding, as on a straight wall, and afterward be pushed against the bridge-wall, as is commonly required; and, furthermore, concaving and convexing the bridge-wall in this manner 60 gives it a reverberatory effect, which is desirable.

I represents the combustion-chamber between the bridge-wall and rear end of the furnace, which chamber has concaved so much of 65 its walls as is below the plane of the crown-sheets of the boiler, (see Figs. 1 and 5,) or, in other words, has a concaved bottom extending

up into its side and end walls, which bottom is grooved, and the rear end wall and the bridge-walls of the furnace are perforated to receive 70 a concaved trough, *k*, in which is operated a screw-conveyer, *K*, journaled in suitable hangers, and provided on its rear end, which projects through the furnace, with a crank, *l*, for manipulating the conveyer, the outer end of the 75 trough being closed by a suitable disk. This conveyer, when operated, serves to draw out of the furnace the accumulation of ashes and fine particles of coal which escape over the bridge-wall into the combustion-chamber, and 80 also the sand and grit given off by the walls of the combustion-chamber by reason of the intense heat to which the walls are subjected. Concaving the walls of the combustion-chamber causes these substances to accumulate in 85 the conveyer-trough, and not form a layer destroying the reverberatory and radiating power, as they would do if the bottom of the chamber were not inclined at a sufficient angle to cause the particles to roll into the trough, and 90 by the term "incline" it should be understood that, so far as an effective operation of the conveyer is concerned, the bottom of the combustion-chamber may be V-shaped, instead of concave. In this connection it should be stated 95 that the forward end of the conveyer is closed, and that the shaft of the conveyer may be projected and operated in the ash-pit, instead of at the rear of the furnace.

Arranged in the combustion-chamber, just 100 above and transversely of the conveyer, are a series of bars, *M*, pivoted at their lower edges to the conveyer-trough by means of lugs, (see Figs. 2 and 5,) and at their upper edges by lugs to a rod, *m*, which, passing through, is operated from the rear end of the furnace to swing the bars, on the same principle of the slats to a shutter, to cut off or open communication between the combustion-chamber and conveyer, as the case may be. These bars are 105 hollow, and provided with openings through which air is introduced into the combustion-chamber, as hereinafter described, the purpose of having these openings on the rear side of the bars being twofold—namely, that of supplying the air in the direction with the draft of the furnace, so as not to impede but augment the draft, and so that the openings may not become filled with ashes, &c., coming over the bridge-wall during the operation of the 110 conveyer, at which time the bars are closed upon each other, as shown in Fig. 2, to prevent lighter particles rising. These openings may be elongated and extend the length of the bars, or consist of a series of perforations in 115 each bar; and in either construction the series of bars serve to divide the air-current, so that it will effectually commingle with the products of combustion escaping over the bridge-wall, the pivotal movement of the bars serving to regulate the volume of the air-current, or to cut it entirely off, as above described.

Opening upon the rear end of the furnace, and formed in the side walls thereof, are air

inlets or chambers N, from which air-passages (shown in dotted lines, Fig. 1, and full lines, Fig. 5) lead to an air-chamber, n, surrounding the conveyer-trough, into which chamber the hollow bars open and receive their supply of air. Chamber n may or may not be lined, as desired, by a sheet-metal trough, and opens at the rear end of the furnace, where it is closed by suitable doors, O, through which a supply of air may be taken, instead of taking it through the walls of the furnace and heating the air during its passage; or it may be used in connection with the heated passages, to supply an increased volume of air.

15 Supported by suitable angle-irons, p, resting on the boiler, is a boiler-covering, P, preferably of fire-brick, but may be of any other suitable material, which covering has an edge-support on flat bars q, resting upon and extending from one angle-iron c to the other, said bars, in fact, forming a base-support for the cover. It will be seen that the covering, not being anchored, is free to rise and fall with the boiler during the expansion and contraction of the same, but effectually prevents the radiation of heat from the same, and by its rising and falling relieves the furnace-walls from strains, which frequently affect their stability, and is therefore an important feature 30 of my invention. When the expansion of the boiler lifts the covering above the flanges of the furnace, the escape of heat under the edges of the lining may be prevented by a brick-work or other suitable filling which will not 35 interfere with the movement of the lining.

Practical experiment with my furnace has demonstrated that, with the supply of air cut off from the combustion-chamber, the degree of heat is much higher than in furnaces having angular combustion-chambers, bridge-walls, and ash-pits, which result can only be attributable to the reverberatory effect attained by my construction, and is due, mainly, to the form of the combustion-chamber. With the 45 supply of air cut off from the combustion-chamber when firing up, the volume of smoke is not materially decreased, and the flame is dark and heavy and advances only slightly beyond the bridge-wall; but with a supply of 50 air through the hollow bars to the combustion-chamber the smoke instantly disappears, and a continuous flame darts forward to the rear end of the furnace and some two feet or more into the flues of the boiler, and little or no smoke 55 appears at the stack. These results are due, partly, to supplying and the manner of supplying air to the products in the combustion-chamber, but as a whole to the reverberatory effect of the furnace, combined with the air-supply, 60 the reverberatory effect of the furnace serving to raise the temperature of the products of combustion, to cause them to fully ignite when in contact with the air, the ignition of these products in the combustion-chamber establishing a uniform degree of heat over the entire surface of the boiler projecting into the fire and combustion chambers. The outer ends

of the air-chambers N are shown as provided with a net-work of brick or iron, to divide the current; but this is not material to my invention, nor is the form of conveyer shown, for any other form may be substituted, or a scraper 70 may be employed to the same end.

By reference to Fig. 4 it will be seen that the side linings of the fire-chamber and the supplemental bridge-wall are in effect a supplemental furnace, protecting and adapted to be removed from the furnace proper when burned out and be replaced with new material without disturbing the same; hence the durability of the furnace proper is very materially increased.

As will be observed, the linings and supplemental bridge-wall very materially diminish the area of the grate, and with it the fire-surface of the furnace; but practical use has demonstrated that with the above-described construction less grate-surface and a correspondingly-diminished amount of fuel are required for successful operation than in furnaces constructed in the ordinary way.

Having thus described my invention, what I claim, and desire to secure by Letters Patent, is—

1. The combination, in a furnace, of a bridge-wall, and a combustion-chamber arranged in the rear of and extending in a plane below the top of said bridge-wall, said combustion-chamber having the masonry of its longitudinal sides and bottom concaved or inclined to a uniform depth, so that the longitudinal line thereof shall be in a horizontal plane, and provided with means of access for the removal of accumulations without interrupting the operation of the furnace, substantially as described. 95

2. The combination, in a furnace, of a bridge-wall, and a combustion-chamber arranged in the rear of and extending in a plane below the top of said bridge-wall, said combustion-chamber having the masonry of both sides and ends 100 and its bottom concaved or inclined to a uniform depth, so that the longitudinal lines of the sides and bottom shall be in a horizontal plane, and provided with means of access for the removal of accumulations without interrupting the operation of the furnace, substantially as described. 115

3. The combination, in a furnace, of a bridge-wall, a combustion-chamber in the rear thereof, and a conveyer arranged in the masonry 120 forming the bottom of said combustion-chamber, and adapted to remove the accumulations in said chamber, substantially as described.

4. The combination, in a furnace, of a combustion-chamber arranged in the rear of the fire-chamber and a conveyer arranged within and in a plane below the bottom of said combustion-chamber, and adapted to remove the accumulations therein, substantially as described. 125

5. The combination of the combustion-chamber, the bottom of which is a contiguous part of the masonry of the side walls of the boiler-setting, and is grooved to receive accu- 130

mulations, and means for removing such accumulations, substantially as described.

6. The combination, with the combustion-chamber, of the series of pivoted and hollow bars forming air-inlets, and means for operating said bars, substantially as described.

7. The combination, with the combustion-chamber, and with the receptacle for the accumulations, of the intermediate swinging bars and means for operating the same, substantially as described.

8. The combination, in a furnace, of a combustion-chamber constructed in the masonry thereof and arranged in the rear of the fire-chamber, the accumulation-receptacle in the bottom of the combustion-chamber, an air-chamber surrounding the receptacle, and air-inlets opening into said air and combustion chambers, substantially as described.

20 9. The combination, with a furnace, of a

bridge-wall the front face of which is convex and its extremities joining the sides of the furnace concaved, as at *i*, substantially as and for the purpose described.

10. In a steam-boiler furnace, the combination, with the boiler, of a covering conforming in shape to the upper portion of and supported by the boiler, and detached from the walls of the furnace, between which the boiler is suspended, substantially as described.

11. The combination, with the boiler, the supporting-lugs, and the side walls of the furnace, of bars supported by and connecting said lugs, and an arched covering resting on the bars, all substantially as described.
